UNITED STATES PATENT OFFICE.

FREELAND D. LESLIE, OF MILTON, MASSACHUSETTS, ASSIGNOR TO BRE MANUFACTURING COMPANY, OF HYDE PARK, MASSACHUSETTS, A CORPORATION OF MASSACHUSETTS.

FLUSHING TANK.

Application filed December 21, 1920. Serial No. 432,353.

To all whom it may concern:

Be it known that I, FREELAND D. LESLIE, a citizen of the United States of America, and a resident of Milton, in the county of Norfolk and Commonwealth of Massachusetts, have invented certain new and useful Improvements in Flushing Tanks, of which the following is a specification.

This invention relates to flushing tanks or reservoirs and particularly to devices of this character used in connection with water closets and the like.

The main object of the invention is the production of a non-sweating tank of simple construction which will have great rigidity and be well ventilated.

The invention consists primarily of an open-work wooden frame having its front and sides covered with an enameled sheet metal plate, said frame being provided with means for supporting an inner water receptacle of earthenware.

The invention further consists of certain novel features of construction and arrangement of parts which will be understood readily by reference to the description of the drawings and to the claims to be hereinafter given.

For the purpose of illustrating the invention, one preferred form thereof is illustrated in the drawings, this form having been found to give satisfactory and reliable results although it is to be understood that the various instrumentalities of which the invention consists can be variously arranged and organized and the invention is not limited to the precise arrangement and organization of these instrumentalities as herein shown and described except as required by the scope of the appended claims.

Of the drawings:

Figure 1 represents a plan view of a flushing tank embodying the principles of the present invention, with the cover removed.

Figure 2 represents a section of the same on line 2, 2, on Fig. 1, with the cover in place.

Figure 3 represents a transverse section of the same on line 3, 3, on Fig. 2.

Figure 4 represents a vertical section of the body of the tank looking toward the front, and

Figure 5 represents a similar view of the body of the tank looking toward the rear.

Similar characters indicate like parts

throughout the several figures of the drawings.

In the drawings, 10 is a framework of wood having the bottom 11 and ends 12.

The rear edges of the ends 12 are connected by boards 13 and 14 which are separated from each other as shown in the drawings.

The upper board 13 is inclined in its lower edge as indicated at 15 in order to provide a means of mounting the framework upon a cleat secured to the wall of the building.

The front edges of the ends 12 are connected by the strips 16 and 17 having grooves formed longitudinally thereof into which project the reduced ends of vertical strips 18.

The bottom board 11 of the framework 10 is provided with an opening 19 for the outlet pipe and is also provided with an opening 20 for the inlet pipe.

One of the vertical strips 18 is provided with a hole 21 for the valve-operating mechanism.

The front and sides of the wooden framework are covered by means of a metal plate 22 and this plate 22 has flanges 23 projecting onto the rear face of the framework 10 and secured thereto.

The metal plate 22 is also provided with top flanges 24 and bottom flanges 25 which are secured in any well-known manner to the top and bottom of the framework 10.

Resting upon the flanges 24 is a projecting flange 26 of a lining member 27 inserted within the upper end of the framework 10. This lining member 27 has formed thereon a plurality of inwardly extending supporting members 28.

Within the framework 10 and removed from the walls thereof is an earthenware water container 29 having at its upper end shouldered projections 30 resting upon the supporting members 28.

The water container 29 is provided with openings 32 and 33 in the bottom thereof in alignment with the openings 19 and 20 in the bottom board 11 of the wooden framework 10.

Projecting upwardly from the upper edges of the wooden framework 10 are a plurality of dowels 34, the upper ends of which are adapted to extend into holes 35 in the cover 36 which is preferably made of wood and covered with a sheet metal plate 37 as indicated in the drawings.

Extending through the bottom board 11

are a plurality of screws 38, the threaded ends of which extend into a supplemental bottom board 39 covered with sheet metal 40 as indicated in the drawings.

5 The metal plate 22 and the plates 37 and 40 are all enameled so that when the flushing tank is assembled the appearance is that of a porcelain tank.

10 The rear edges of the bottom board 11 and the supplemental bottom board 39 are clear of the wall to which the flushing tank is secured thereby leaving a passage 41 through which the air may pass upwardly around the wall of the earthenware water 15 container 29.

By using the earthenware water container 29 free from the walls of the framework 10, the tank is made sweatless and as a consequence the outer metallic casing thereof is 20 kept dry and will not deteriorate.

Should there be any leakage in the water container 29 it will become evident by the drippings through the passage 41.

25 By the use of the earthenware water container 29 a great saving in cost is made over a tank in which an inner tank is required made of copper or some similar metal.

The completed tank is less expensive to construct than porcelain tanks, of less 30 weight and therefore easier to transport and in transportation and when installed is less liable to be injured.

When the tank is used as a low-down tank, the supplemental bottom plate may be 35 dispensed with if desired and when said tank is installed near the top of the wall the cover may be dispensed with.

It is believed that the operation and many 40 advantages of the invention will be understood readily without further description.

Having thus described my invention, I claim—

1. The combination in a flushing tank of a wooden frame open at the top; a sheet

metal plate covering the front and sides 45 thereof; and an earthen water-container supported within said frame with continuous space between its outer walls and the inner walls of said wooden frame.

2. The combination in a flushing tank of a 50 wooden frame open at the top; a sheet metal plate covering the front and sides thereof; and an earthen water-container supported within said frame free from the walls thereof by an outwardly extending flange 55 formed on said container and resting on members extending inwardly from the inner walls of said wooden frame.

3. The combination in a flushing tank of a 60 wooden frame open at the top; a sheet metal plate covering the front and sides thereof and secured thereto; a lining for the upper end of said frame having an outwardly extending flange projecting over the top edge of the frame and provided with 65 inwardly extending supporting members; and a water-container supported by said members and provided in its bottom with a discharge opening.

4. The combination of a flushing tank of 70 a wooden frame open at the top and consisting of a perforated bottom, imperforate sides, horizontal and separated back strips connecting said sides and of which the lower is above the upper face of the bottom, and 75 horizontal separated front strips connecting said sides at the top and bottom and connected by a plurality of vertical strips; and a metal plate covering the front and sides of said frame.

80 Signed by me at 746-7 Old South Bldg., Boston, Mass., this 10th day of December, 1920.

FREELAND D. LESLIE.
